UNITED STATES PATENT OFFICE.

DAVID BROWN, OF JERSEY CITY, NEW JERSEY.

FIRE-ESCAPE.

1,119,802.

Specification of Letters Patent.

Patented Dec. 8, 1914.

Application filed March 17, 1914. Serial No. 825,277.

To all whom it may concern:

Be it known that I, DAVID BROWN, a citizen of the United States, residing at Jersey City, county of Hudson, and State of New Jersey, have invented new and useful Improvements in Fire-Escapes, of which the following is a specification.

This invention consists of a new and improved form of fire escape which is particularly adapted for use in large buildings where people congregate in large numbers, such as factories, schools, office buildings, hotels, etc.

Folding fire escapes heretofore have been built with the steps or rungs of the ladder portion in a perpendicular line, when the escape is opened for use such for example as typified in U. S. Letters Patent No. 723,194 issued to me on March 17th 1903. This perpendicular construction is both dangerous and inconvenient, especially when used by women as experience has demonstrated that they become frightened and loose their hold when coming down a perpendicular ladder, and by reason of their dresses catching on the rungs of a straight ladder.

The present invention obviates these difficulties by reason of its construction, which consists of a series of stationary platforms, with a swinging platform pivotally connected to each of the platforms. A ladder is pivoted to each swinging platform and it has its upper end tilted against a movable floor section carried by a swinging platform.

The forward portions of the swinging platforms are pivotally connected to a vertical ladder which rests on the ground when the escape is in operation. This ladder together with the swinging platforms can be swung upwardly when the fire escape is folded. The swinging platforms in this device fold into the stationary platforms while the tilted ladders slide upwardly and move the floor sections inwardly so that all the parts with the exception of the vertical ladder will be housed in the stationary platforms. The invention thus contemplates a fire escape which can be folded into small compass and also by means of counter weights can be let down or unfolded by a single operator without breakage of the parts.

In the accompanying drawings Figure 1 is a side elevation showing the device ready

for use. Fig. 2 is a similar view showing the device folded up. Fig. 3 is a front elevation of Fig. 1. Fig. 4 is a plan view of the same. Fig. 5 is a detail section of a movable floor taken along the line *x-x* of Fig. 4. Fig. 6 is a similar section taken along the line *y-y* of the same. Fig. 7 is a detail vertical section showing the parts folded. Fig. 8 is a front elevation of a portion of a tilted ladder.

The device consists essentially of a series of stationary platforms having rails *a* secured to the outside of a building *b*, there being of course one platform for each story or floor of the building. These platforms are constructed of floor rods *c* and vertical rods *d* connected to the upper and lower rails *a* in the usual way. Pivots connected to each of the stationary platforms at *e* is a swinging platform provided with rails *f* having floor rods *g* and vertical rods *h* fixed to the upper and lower rails as shown. The swinging platform extends from an opening formed in the front of the stationary platform see Fig. 4. Movably mounted on each of the platforms *f* is a floor section consisting of a frame *i* having transverse floor rods *j*, as indicated in Fig. 4, secured to the said side rails. These side rails are provided with a series of stops *k* each stop having secured to it a bolt *m* with a head *n*. The stem of the bolt extends through a hole *o* see Fig. 6, located in a rail of the swinging platform. To each of the swinging platforms is pivoted at *p* a slanted or tilted ladder *q* having side rails or banisters *r* swingingly mounted at *s* see Fig. 8, so as to fold toward each other when the escape is out of action or closed. To the forward portion of each swinging platform *f* is pivotally connected at *t* a vertical ladder including side rails *u* with rungs *v* parallel to the floor rods of the swinging platforms. This ladder extends from the top swinging platform and far enough below the lower platform to rest on the ground when the escape is in use.

A chute *w* is pivoted at *z* to the lower portion of the vertical ladder and it has its upper end tilted against the movable floor of the lower platform. This chute is also provided with hand rails *r* which fold inwardly the same as the tilted ladders noted above. This chute may be in the form of a ladder, but the construction shown is preferred so that a person using the escape can

slide the last distance instead of climbing it. To each hand rail *r* a cable 13 is attached and the other end is attached to the ladder *g* or chute *w*, so that when the device 5 is opened the hand-rails or banisters will be held in open position as shown in Fig. 3, and will fold of their own weight when the device is closed, see Fig. 8. To the center of the top swinging platform *f* is attached a 10 chain or cable 14 passing over a pulley 15 secured to the outside of the building, and over another pulley 16 inside the building and attached at its other end to a counterbalance 17. While the counterbalance 17 is 15 here shown in a receptacle 18 close to the wall of the building it will of course be understood that the well and counterbalance may be constructed in any desired part of the building. Attached to the long outer 20 vertical ladder *u*, either at 19 or adjacent to each swinging platform *f* are cables 20 passing over a series of pulleys 21 and 22, and attached to a counterbalance 23. Attached to the bottom of the ladder *u* is a 25 cable 24 for pulling the device from its folded position shown in Fig. 2 to its operative position shown in Fig. 1. Various devices may be used to accomplish this result, for example in a factory or hotel an 30 electrical appliance might be used so that the device may be put into operative position simply by pushing a button. The weights 23 may be omitted in low buildings, but in buildings having three or more stories 35 it would be necessary to have a very large and heavy weight 17 to counterbalance the weight of all the platforms, therefore it has been found more practicable to have the small weights connected to each platform to serve as auxiliaries to the large 40 weight.

Each ladder *g* is tilted against one of the movable floors when the ladder is down, but when the ladder is swung upward as shown, 45 in Fig. 2, the movable floor *i* will be pushed toward the front of the building, and thus give space for the swinging ladder *g* to slide between the movable floor and the vertical ladder *u*. When the movable floor 50 is in this position the bolts *m* move with the floor *i* until the head *n* of each bolt strikes the opposite side of the rail *f* where it is

stopped, thereby limiting the movement of the movable floor. It will be seen that when the escape is open as indicated in Fig. 1 the 55 bolts *m* will gravitate downward with the movable floor *i* until the stops *k* strike on to the top of the rails *f* hence limiting the downward movement of the movable floor. It will be seen that each tilted ladder has 60 its lower end swingingly connected to a swinging platform and the upper end resting against the movable floor of the preceding platform.

I claim:

1. In a fire escape the combination with a series of stationary platforms, of a swinging platform pivotally connected to each of the platforms, a ladder pivoted to each swinging platform and slidingly tilted 70 against a swinging platform.

2. In a fire escape the combination with a series of stationary platforms, of a swinging platform pivotally connected to each of the platforms, a ladder having side rails 75 pivotally connected to each swinging platform and slidingly tilted against a swinging platform, a pair of hand rails swingingly connected to the side rails of the tilted ladder.

3. In a fire escape the combination with a series of stationary platforms, of a swinging platform pivotally connected to each of the platforms, each swinging platform being provided with a movable floor, a ladder 85 pivoted to each swinging platform and slidingly tilted against the movable floor of the preceding platform.

4. In a fire escape the combination with a stationary platform, of a swinging platform 90 provided with a movable floor, a vertical ladder having side rails pivoted to the end of the swinging platform, a chute or ladder pivoted to the lower portions of the vertical ladder and slidingly tilted against the mov- 95 able floor of the swinging platform.

In testimony whereof I have hereunto set my hand in the presence of two subscribing witnesses.

DAVID BROWN.
